His Attorney.

UNITED STATES PATENT OFFICE.

ALBERT H. SIMMONS, OF WHEATON, ILLINOIS, ASSIGNOR TO EDISON ELECTRIC APPLIANCE COMPANY, INCORPORATED, OF CHICAGO, ILLINOIS, A CORPORATION OF NEW YORK.

DESIGN FOR AN ELECTRIC-HEATER BASE OR SIMILAR ARTICLE.

Application filed January 28, 1927. Serial No. 20,525. Term of patent 14 years.

To all whom it may concern:

Be it known that I, ALBERT H. SIMMONS, a citizen of the United States, residing at Wheaton, in the county of Du Page, State of Illinois, have invented a new, original, and ornamental Design for Electric-Heater Bases or Similar Articles, of which the following is a specification, reference being had to the accompanying drawing, forming a part thereof.

The single figure of the drawing is a perspective view of a design for an electric heater base embodying my new design.

I claim:

The ornamental design for an electric heater base or similar article substantially as shown.

In witness whereof, I have hereunto set my hand this 25th day of January, 1927.

ALBERT H. SIMMONS.
